UNITED STATES PATENT OFFICE.

CLARENCE J. WUESTNER AND ALFRED G. SCHUMANN, OF HIGHLANDTOWN, MARYLAND; SAID WUESTNER ASSIGNOR TO SAID SCHUMANN.

FURNACE.

1,160,806.

Specification of Letters Patent.

Patented Nov. 16, 1915.

Application filed July 8, 1914, Serial No. 849,760. Renewed September 15, 1915. Serial No. 50,904.

To all whom it may concern:

Be it known that we, CLARENCE J. WUESTNER and ALFRED G. SCHUMANN, citizens of the United States, residing at Highlandtown, in the county of Baltimore and State of Maryland, have invented certain new and useful Improvements in Furnaces; and we do hereby declare the following to be a full, clear, and exact description of the invention, 10 such as will enable others skilled in the art to which it appertains to make and use the same.

This invention contemplates new and useful improvements in oil burners and resides 15 in the provision of a novel oil burner that is particularly designed for use in connection with open hearth furnaces and which will operate to provide a maximum heat with a minimum fuel consumption and is constructed 20 so as not to become injured by the heat from the furnace or device to which it is attached.

Another object is to provide novel means 25 for moving the burner into and out of the furnace and which operates when two burners are employed on opposite sides of the furnace to alternately move the burners into the furnace and inject fuel when so extended so that when one burner is discharging the 30 other is withdrawn from the furnace and is protected against becoming injured by the intense heat from the furnace.

Another object is to provide means for 35 cooling the burner when in withdrawn position so that its proper operation is insured.

Another object is to provide a novel valve arrangement which permits the fuel to be fed to the furnace when the burner is in extended position only.

40 This invention further aims to improve oil burners so as to render them more practical, reliable and efficient in operation, inexpensive to manufacture and more commercially desirable.

45 The above and additional objects are accomplished by such means as are illustrated in the accompanying drawings, described in the following specification and then more particularly pointed out as claimed.

50 With reference to the drawings, wherein we have illustrated the preferred embodiment of our invention as it is reduced to practice, and throughout the several views of which similar reference numerals designate corresponding parts, Figure 1 is a dia-

grammatic view showing our improved burner and coöperating parts attached to an open hearth furnace of the ordinary type, said furnace being shown in section, Fig. 2 is an enlarged plan view of the means for moving the burners into and out of the furnace and oil and air valves, Fig. 3 is a detail longitudinal sectional view taken through the operating cylinder for reciprocating the burner, Fig. 4 is a longitudinal sectional view taken through one of the valves for controlling the oil and air discharge, Fig. 5 is a longitudinal sectional view of the valve to control the operating means for the burner, Fig. 6 is a longitudinal sectional view taken through the cooling means for the burner, Fig. 7 is a detail sectional view taken longitudinally through a modified form of burner showing adjusting means therefor, Fig. 8 is a detail sectional view taken through the burner at the discharge end thereof at a plane at right angles to that shown in Fig. 7, and Fig. 9 is a fragmentary longitudinal sectional view through the burner tip.

Referring to the drawings by characters of reference, A designates as an entirely an open hearth furnace of the ordinary and well known type and to which our improved burner is attached. In the application of 85 our improved burner to the furnace A, a burner is provided in each side of the furnace and is provided with mechanism whereby it is moved into and out of the furnace and discharges fuel when in extended position.

Our burner consists of an outer cylindrical shell 1 that has its discharge end 2 provided with an angularly disposed flange 3 so that an elongated discharge opening is provided 95 thus producing a fan like flame. Mounted within the outer shell 1 is a tubular oil pipe 4 provided with a flared discharge end 5 and being of considerably less diameter than that of the outer shell 1. One end of the outer shell 1 is turned in an internally threaded nipple 6 that is formed on one side of an approximately rectangular and hollow coupling member 7. A compressed air pipe 8 is secured to the coupling member 7 and communicates therewith in such manner that the air may readily flow through the shell 1 and out at the discharge end 2 thereof. In the side of the coupling member 7 opposite to the point where the pipe 8 is connected is 110

formed a longitudinal slot 9 through which is slidably extended an oil pipe 10. A two way coupling member 11 connects the pipes 4 and 10 with each other, within the coupling member 7. The coupling member 11 is enlarged at the rear end thereof and formed with a slot or recess 12 therein, in which slot or recess 12 is swiveled the head 13 of an adjusting screw 14. The adjusting screw 14 is turned through an opening 15 formed in the rear wall of the coupling member 7 and extended beyond said wall and squared on its outer end as at 16. A lock nut 17 is turned upon the extended threaded portion of the adjusting screw 14. It is to be understood that this adjusting arrangement is provided only when the burner is to be held stationary and not equipped with the reciprocating mechanism to be later more fully described. When the burner is to be reciprocated it is constructed as shown in Fig. 2, a piston, as will be later more fully described and which is designated 18, is secured in an opening in the rear wall of the coupling member 7, as at 19.

To prevent leaking of the air from the member 7 through the slot 9 therein we provide a closure plate 20 that is secured in any suitable manner upon the pipe 10 and 30 slides upon the outer face of the coupling member 7 so as to at all times close the slot 9 therein. By adjustment of the pipe 4 to move the discharge end 5 thereof relative to the discharge end 2 of the member 35 1, the character of flame may be regulated or changed as desired. The flange 3 in partially covering the discharge opening in the shell 1 deflects the air rushing through said shell in such manner that it is thoroughly 40 mixed with the oil which discharges from the pipe 4 at the end 5 thereof, thus a proper mixture of oil and air is discharged into the furnace or apparatus to which the burner or burners are attached.

45 We provide cooling means to be mounted within the furnace and which prevents heat therefrom from injuring the burner. The cooling means is mounted in the ports B and C in the sides of the furnace and which 50 communicate with the fire box D. In these ports B and C the burners are arranged as clearly shown in Fig. 1 in the drawings. The cooling means consists of an outer cylindrical shell 21 and an inner shell 22 similar to the one 21 but of considerably less 55 diameter. A cylindrical sleeve or coupling member 23 provided with an inwardly turned outer end to provide an annular flange 24 which is spaced from the member 23 receives at one end the outer end of the shell 21 and the shell 22 at the flange 24 thereof. The flange 24 serves in combination with the shell 22 to seal the compartment formed by the member 60 65 21 at the outer end thereof. A cylindri-

cal member 25 receives the other end of the member 21 and is provided with a central web plate 26 through which is inserted the inner shell 22. A flanged packing sleeve 27 is mounted upon the shell 22 and is inserted into the member 25 at the rear end thereof. The shell 22 is of sufficient size to slidably receive the shell 1 of the burner so that said shell 1 may extend beyond the shell 22. The shell 21 is secured 70 in any suitable manner within each of the ports B and C so that the inner end thereof is spaced from the fire box D. A water inlet pipe 28 communicates with the shell 21 at one end of said shell and is connected with the member 25. An outlet pipe 29 is connected with the coupling member 23 and communicates with the shell 21. It will be readily seen that water may be caused to circulate in the chamber formed by the shell 21 about the pipe 22 which surrounds the shell 1 of the burner. The circulation of cold water will serve to cool the burner in such manner that the intense heat from the furnace will have no effect thereupon. The cooling means hereinbefore described acts to slidably support and guide the burner as well as to cool the same.

The means for reciprocating the burner so that it is moved into and out of the furnace consists of three cylinders 30, 31 and 32 that are secured to one another in any suitable manner. The cylinder 30 is arranged between the cylinders 31 and 32 and has mounted therein a piston 33 that is connected to the piston rod 18 previously described. A suitable packing member 34 slidably receives the piston rod 18 at one end of the cylinder 30. Air pipes 35 and 36 are secured to the cylinder 30 and communicate therewith at points adjacent to its ends. The pipes 35 and 36 connect with a valve casing 37 in which an ordinary D slide valve 38 is mounted. A valve casing 39 similar to the one 37 and provided with a valve similar to the one 38 is mounted adjacent to the one 37 and adapted to control mechanism for reciprocating the burner in the other side of the furnace. It will be understood that in a furnace of the character shown in Fig. 1 we provide burners on opposite sides thereof and identical mechanism for operating the burners. The valve stem 40 is common to the valves in the casings 37 and 39 so that the valves work 110 alternately resulting in the alternate reciprocation of the burners in the ports B and C. In each valve casing 37 we provide a central inlet port 41 that is arranged to communicate with outlet ports 42 and 43 115 which communicate respectively with the pipes 35 and 36. An air pipe 44 is connected with a suitable source of compressed air supply and with the port 41. The ports 41, 42 and 43 are formed in the 120 125 130

lower part of the casing 37 while the pipes 35 and 36 communicate therewith. When the valve 38 is in the position shown in Fig. 5 in the drawings, the air is conducted from 5 the port 41 up through the valve and into the port 42 and out through the pipe 35 to the cylinder 30 and to the forward end of the cylinder. This results in the outward movement of the piston and the withdrawal 10 of the burner from the furnace from a position illustrated on the left hand side of Fig. 1 to that on the right hand side. When the valve 40 moves to the other side of the casting 37 and communicates the ports 41 and 15 43 with each other the air is admitted to the outer end of the cylinder 30 and the piston moved so that the burner is inserted into the furnace and a charge of fuel injected as will be later more fully described. 20 The valves 38 are operated through the medium of a pivoted lever 45 that is pivoted intermediate its ends as at 46 to a suitable support not shown and is loosely connected as at 47 to the valve rod or stem 40 25 centrally of the ends of said valve rod or stem. The upper end of the lever 45 is pivoted as at 48 to a reciprocatory beam or rod 49 that is connected with a suitable source of power and operated to move back and 30 forth or reciprocate. It will be readily seen that the valve 38 will operate to alternately admit air to either side of the piston 33 in the piston cylinder 30.

A pipe 50 serves to connect the cylinder 31 35 with a suitable supply of air, not shown. Mounted within the cylinder 31 is the other end of the air pipe 8 that is connected with the shell 1 of the burner. The cylinder 31 is closed at both ends and said pipe 8 is 40 slidable through a suitable packing collar 51. A valve member 52 provided with a beveled outer face is mounted upon the inner end of pipe 8 and arranged to seat within a frusto-conical seat 53. 45 The valve 52 is provided with an opening 54 therein which communicates with the pipe 8 and is to be closed when the valve is seated with the seat 53. The seat 53 is mounted upon a pin 54^a that is threaded at 50 its outer end and inserted through the outer end of the casing 31. A nut 55 is turned on the outer end of said pin. A helical expansion spring 56 is mounted upon said pin 54^a and engages the adjacent wall of the cylinder 31 and the seat 53 at its terminals. 55 This spring 56 serves to yieldingly hold the seat 53 in extended position and will yield when the valve 52 is moved toward the seat so as to provide a positive seating of the valve and to prevent flow of air thereinto 60 and through the pipe 8. When the valve 52 is spaced from the seat 53 as shown in Fig. 4 in the drawings, the air passes into the cylinder 31 through the pipe 50, through the 65 opening 54 in the valve 52 and out through

the pipe 8 into the shell 1 of the burner as previously described. The pipe 8 is connected with the coupling member 7 which is in turn connected with the piston 18, thus it will be seen that the valve 52 is open only 70 when the burner is extended into the furnace into position for discharging fuel into the fire box D.

A supply pipe 57 communicates with the cylinder 32. The supply pipe 57 is connected with a suitable source of supply and is arranged to communicate with the pipe 10 which is extended into the cylinder 32 in the same manner as is the pipe 8 and is provided with an identical valve arrangement 75 80 which operates only when the piston rod 18 is extended. It will thus be seen that the valves in the cylinders 31 and 32 operate simultaneously when the burners are extended into the furnace to permit the flow 85 of air and oil to the burners.

The furnace A is equipped with flue passages E and F which communicate with the passages C and B which lead to the fire box D. When the burner in the port C is in extended position as shown in Fig. 1 in the drawings, the burner in the port B is drawn so that it is housed within the cooling means consisting of the shells 22 and 23 and the draft or products of combustion pass into 90 the port B down the port or passage E and out through the stack. A similar operation is had when the burner in the port B is extended and the one in the port C withdrawn. Steam as well as air may be used 95 for blowing the oil through the nozzle.

In practice, we have found that the form of our invention, illustrated in the drawings and referred to in the above description, as the preferred embodiment, is the most efficient and practical; yet realizing that the conditions concurrent with the adoption of our device will necessarily vary, we desire to emphasize the fact that various minor changes in details of construction, proportion and arrangement of parts may be resorted to, when required, without sacrificing any of the advantages of our invention, as set forth.

What is claimed is:—

1. In a device of the character described, the combination with a furnace of fuel injecting means arranged to inject fuel therein, and automatic means to alternately move said fuel injecting means into and out of the furnace.
2. In a device of the character described, the combination with a furnace of fuel injecting means mounted on opposite sides of the furnace and arranged to inject fuel 120 therein, means to alternately move said fuel injecting means into and out of the furnace, and means to automatically admit oil and air to the injecting means at the time it is extended into the furnace and automatically 125

4
cut off the supply of oil and air to the injecting means when it is withdrawn from the furnace.

3. The combination with a furnace of
5 burners mounted for reciprocation into and
out of the furnace on opposite sides thereof,
cylinders, pistons mounted within the cyl-
inders, piston rods connected with the pis-
tons and the respective burners at their ends
10 and slidable through the cylinders, cylinders
mounted on opposite sides of said first cyl-
inders, oil and air feed pipes communicating
respectively with said last named cylinders,
valves mounted within said last named cyl-
inders and to control the supply of oil and
15 air to the burners, pipes connecting said
valves with the burners, and slidale through
said last named cylinders, said valves car-
ried on the inner ends of said pipes, valve
20 seats within said last named cylinders to
coöperate with said valves when the burn-
ers are withdrawn from the furnace and
means to alternately provide a supply of
air on opposite sides of the piston in said
25 first cylinder.
4. The combination with a furnace of
burners mounted for reciprocation into and
out of the furnace on opposite sides thereof,
cylinders, pistons mounted within the cyl-
inders, piston rods connected with the pis-
30 tons and the respective burners at their ends
and slidale through the cylinders, cylinders
mounted on opposite sides of said first cyl-
inders, oil and air feed pipes communicating
respectively with said last named cylinders,
35 valves mounted within said last named cyl-

inders and to control the supply of oil and
air to the burner, pipes connecting said
valves with the burners, and slidale
40 through said last named cylinders, said
valves carried on the inner ends of said
pipes, valve seats within said last named
cylinders to coöperate with said valves
when the burners are withdrawn from the
45 furnace, means to alternately provide a
supply of air on opposite sides of the pis-
ton in said first cylinder, and said means
consisting of two way valves connected with
said first named cylinder and a suitable
50 source of compressed air supply.

5. The combination with a furnace of
burners mounted for reciprocation into and
out of the furnace, automatic means to move
the burners alternatively into and out of the
furnace and automatic means to admit fuel
55 to the burners when the burners are recipro-
cated and cut off the supply of fuel when
the burners are withdrawn comprising cyl-
inders, valves movable within the cyl-
inders and operatively associated with the
60 burner reciprocating means to move simul-
taneously therewith and yielding valve seats
within the cylinders to coöperate with the
valves when the burners are withdrawn.

In testimony whereof we affix our signa-
65 tures in presence of two witnesses.

CLARENCE J. WUESTNER.
ALFRED G. SCHUMANN.
